Patented May 9, 1916.

UNITED STATES PATENT OFFICE.

AMOS A. WYCKOFF, OF SANTA CRUZ, CALIFORNIA, ASSIGNOR TO EGITE MANUFACTURING COMPANY, OF SANTA CRUZ, CALIFORNIA, A CORPORATION OF CALIFORNIA.

BLADE-SHARPENER.

1,182,440.

Specification of Letters Patent.

Patented May 9, 1916.

Application filed June 19, 1915. Serial No. 35,088.

To all whom it may concern:

Be it known that I, AMOS A. WYCKOFF, a citizen of the United States, residing at Santa Cruz, in the county of Santa Cruz and State of California, have invented certain new and useful Improvements in Blade-Sharpener, of which the following is a specification.

This invention relates to blade sharpeners 10 and has more particular reference to a novel device for sharpening safety razor blades and similar articles.

One of the primary objects of the invention is to provide a device of this character 15 which will be simple and compact in construction, which will present two abrading surfaces of different characters, which will hold a blade to be sharpened in proper position and at the proper angle with respect to 20 both of said surfaces, which will be adjustable so that the angle of the blade may be changed to accommodate the device to various types of blades, and which will afford protection to the abrading elements when 25 the device is not in use.

Other objects of my invention and the structural characteristics of one embodiment thereof will be readily appreciated as the same becomes better understood by 30 reference to the following description when considered in connection with the accompanying drawings, wherein—

Figure 1 is a perspective view of a sharpener embodying my invention; Fig. 2 is a 35 similar view of one of the covers with the blade-holder positioned therein; Fig. 3 is a transverse sectional view through the device with both covers in place thereon; Fig. 4 is a fragmentary longitudinal sectional view 40 through the construction shown in Fig. 1; Fig. 5 is a transverse sectional view through the blade-holder; Fig. 6 is a longitudinal sectional view through the holder; Fig. 7 is a plan view of the holder shown in Fig. 6; 45 Fig. 8 is a perspective view of the removable element of the holder; Fig. 9 is a sectional view on the line 9—9 of Fig. 6; Fig. 10 is a sectional view on the line 10—10 of Fig. 6; Fig. 11 is a plan view of a modified 50 form of holder.

From an inspection of the drawings it will be observed that the frame of the holder comprises essentially two plates 13 and 14 spaced apart by spacing blocks 15 and 16 55 at the ends, the plates being rigidly secured

together by rivets 17 or otherwise so as to provide a slot or track 18 between the plates, which slot extends entirely across the frame and substantially throughout the length thereof. The plates which are substantially 60 duplicates of each other are provided with flanges 19 extending around the plates near the margins thereof to provide sockets or holders for a pair of abrading elements. One of these elements designated by reference character 21 is in the form of a hone while the other 22 consists of a stropping pad, the hone being adapted for preliminary sharpening and the stropping pad for 65 finishing purposes. The hone and the pad fit tightly within the flanges 19 and, if preferred, an adhesive may be utilized to securely fasten them in place.

A pair of covers 23 and 24, respectively, 70 are shaped to fit the flanges 19 so as to cover the abrading elements and protect them from dust and dirt when the device is not in use. The covers are substantially of the same size so that they may be interchangeable, and the cover 24 is provided at the four 75 corners with legs or feet 25, preferably of rubber, which serve to support the frame in operative position and to prevent slippage of the same on the surface upon which it rests. It will be obvious that when the cover 23 is 80 removed the hone 21 will be presented uppermost in operative position as shown in Fig. 1 and that when it is desired to use the strop 22 the cover 24 is placed over the hone 21 and the entire frame is inverted so as to present the strop 22 upwardly. A carrier 85 adapted to carry a blade-holder in operative relation to the hone or the stropping pad is designed and arranged to reciprocate longitudinally of the device between the pad and 90 the hone. This carrier comprises a pair of rollers 26 and 27 extending transversely of the slot 18 and rotatably mounted on rods 28 and 29 respectively, which are rigidly connected at their ends to end-pieces 31 and 32. 95 The end-pieces slidingly contact with the edges of the plates 13 and 14 and are each provided with outwardly extending threaded bosses 33 and 34 respectively, and with integral ears or guides 35 and 36. A 100 pair of substantially U-shaped guiding and supporting devices 37 straddle the guides 35 and 36 by which they are maintained in vertical position, and clamping thumb nuts 38 are threaded onto the bosses 33 and 34 to 110

clamp the members 37 in adjusted position. It will be observed that the outer end of the base of each of the members 37 is concave as indicated at 39 to form a support for the blade-holder, to be later described, and that the legs of the other member 37 of the pair serve as guides to retain the holder on the support. By raising or lowering the members 37 on the bosses the height at which the holder will be supported may be varied so as to present the blade carried by the holder at the proper angle to the abrading surface.

The holder comprises two elements 41 and 42 respectively, between which the blades are clamped. The element 41 is shaped to present a flat upper surface and at one end it is equipped with a cap 43 rigidly secured thereto by a rivet 44, said cap presenting an inclined undercut portion 45 for the reception of the similarly shaped head 46 of the element 42. The other end of element 41 is squared as indicated at 47 (Fig. 9) to slidably receive the squared portion of a surrounding sleeve 48 which has an inclined undercut portion 49 adapted to receive the head 46 of the member 42. The extremity of the element 41 beyond the squared portion 47 is threaded to receive a thumb nut 51 by means of which the sleeve 48 may be forced inwardly to firmly clamp the element 42 against the element 41, thereby clamping and holding a blade 52 between the elements. It will be obvious that by loosening the nut 51 the sleeve may be slipped back so as to release one end of the element 42, whereupon the element may be removed by withdrawing it from the cap 43. A blade can be positioned upon the element 41 and the element 42 replaced by slipping one end under the cap 43, pressing the other end down, and then forcing the sleeve 48 into holding position by means of the nut 51. The holder shown in Figs. 1 to 10 inclusive is adapted to hold a double-edged blade but in Fig. 11 I have shown a modified form of holder having a portion thereof cut away as indicated at 52 to receive the back 53 of a single edged blade. In other particulars the holder is substantially like that previously described.

In using the device a blade is first positioned in the holder and then the supporting and guiding devices 37 are set to support the holder the requisite distance above the hone or strop, as the case may be, so that the blade will be presented at the proper angle to the abrading surface. By grasping the cap 43 and the sleeve 48 between the thumb and forefinger the operator may move the carrier back and forth longitudinally of the frame and by a slight turning movement of the fingers at each end of the stroke the blade may be tilted to present the proper edge for the action of the

abrading element. Assuming that the blade is first honed, after the honing is completed the holder with the blade in it is laid aside while the cover 24 is removed from the stropping pad 22 and positioned over the hone. The device is then reversed to present the stropping pad uppermost whereupon the holder may be positioned in the guides 37 and moved back and forth across the strop until the sharpening is completed. By loosening the nuts 38, the blade-holder guiding and supporting devices 37 can be removed, thus enabling the abrading block to be used as a hone and strop for the blade of an ordinary razor. It will also be observed that the adjustable blade-holder guiding and supporting devices serve not only as a means for supporting the blade at any desired or proper angle to the honing or stropping surface, but they also support the blade-holder above or out of rubbing contact with such surface, thus insuring that the latter engages only the edge of the blade.

When the device is not in use the strop and the hone are both covered and protected against dirt and the like, and in order that all the parts may be assembled into compact form I have provided within the cover 23 a pair of spring clips 54 and 55 adapted to receive and retain the blade-holder, thereby preventing it from becoming lost.

My invention and its mode of operation should be fully understood from the foregoing without further description and it should be obvious that various changes in the mechanical details shown and described may be resorted to without departing from the scope of the invention as defined in the following claims.

I claim:

1. In a blade-sharpener, the combination of a hone and a stropping member fixedly mounted in spaced relation so as to present oppositely facing working surfaces, a carrier mounted to reciprocate between said hone and said stropping member, blade-holder supporting and guiding means carried at each end of said carrier, and a blade-holder adapted to be removably engaged with said supporting and guiding means so as to present a blade held thereby in operative relation to either of said working surfaces.

2. In a blade-sharpener, the combination of a frame, a plurality of oppositely disposed abrading elements fixedly mounted therein, a reciprocable carrier extending through said frame between said elements, supporting devices adjustably mounted on said carrier at each side of said frame, and a blade-holder constructed to be removably engaged with said devices so as to present a blade in operative relation to either of said elements.

3. In a blade-sharpener, the combination

of a frame having a central transversely disposed slot, an abrading element mounted in said frame above and one beneath said slot, a reciprocable carrier comprising rollers disposed in said slot and supporting devices disposed at each side of the frame, and a blade-holder removably engageable with said devices.

4. In a blade sharpener, the combination 10 of a pair of abrading elements fixedly mounted in spaced relation so as to present oppositely disposed surfaces, a carrier reciprocable intermediate said elements, each end of said carrier being equipped with a 15 plurality of oppositely extending adjustable supporting and guiding devices, and a blade-holder adapted to be engaged with said devices.

5. In a blade-sharpener, the combination 20 of a frame, a pair of oppositely disposed abrading elements fixedly mounted in said frame, a carrier slidably and permanently connected with said frame, comprising rollers extending transversely of the frame between 25 said elements, and a pair of oppositely disposed guiding and supporting devices adjustably mounted at each end of the rollers in position to receive and guide a blade-holder in operative relation to either 30 of said elements.

6. In a blade-sharpener, the combination 35 of a frame, a pair of abrading elements fixedly mounted in said frame so as to present oppositely facing working surfaces, a pair of interchangeable covers adapted to fit said frame so as to cover said elements, and a plurality of feet mounted on one of

said covers to form supports for the sharpener.

7. In a blade-sharpener, the combination 40 of a frame, a pair of abrading elements fixedly mounted therein, a pair of covers detachably fitting said frame to cover said elements, a blade-holder, and means for supporting said holder in operative relation 45 to either of said elements.

8. In a blade-sharpener, the combination 50 of a frame having a centrally disposed track, an abrading element mounted at one side of said track, a carrier comprising rollers engaged with said track and supporting and guiding devices carried at each end of said rollers, and a blade-holder removably engageable with said supporting and guiding 55 devices.

9. In a blade sharpener, the combination 60 of a pair of abrading elements fixedly mounted so as to present oppositely disposed surfaces, a carrier reciprocably attached to said elements, said carrier being 65 equipped with a plurality of adjustable supporting and guiding devices, and a blade holder adapted to be engaged with said devices.

10. In a blade sharpener, the combination 65 of a frame provided with a track, an abrading element mounted in said frame, a carrier comprising rollers engaged with said track and supporting and guiding devices disposed at each side of the abrading element, and a blade holder removably engageable with said supporting and guiding 70 devices.

AMOS A. WYCKOFF.
